[57]

CLAIM

The ornamental design for a warm-up jacket, as shown and described.

DESCRIPTION

FIG. 1 is a front elevational view of a warm-up jacket showing my new design in use, the broken lines partially showing a human form in both views being for illustrative purposes only and forming no part of the claimed design; and,

FIG. 2 is a rear elevational view thereof.

The partial broken line showings of the human form in FIG. 1 and FIG. 2 are for illustrative purposes only and form no part of the claimed design.

FIG. 1

UNITED STATES PATENT AND TRADEMARK OFFICE
CERTIFICATE OF CORRECTION

PATENT NO. : Des. 353,255
DATED : December 13, 1994
INVENTOR(S) : Rodriguez

It is certified that error appears in the above-identified patent and that said Letters Patent is hereby corrected as shown below:

The title page should be deleted and substitute therefor the attached title page.

Delete drawing sheet and substitute therefor the drawing sheet consisting of Figs. 1 and 2, as shown on the attached page.

Signed and Sealed this

Twenty-ninth Day of October 1996

Attest:

BRUCE LEHMAN

Attesting Officer
